UNITED STATES PATENT OFFICE.

PROSPER L. GOTTSCHALK, OF WAUWATOSA, WISCONSIN.

FORM FOR BUILDING CONSTRUCTION.

Application filed August 3, 1925. Serial No. 47,877.

This invention relates to certain new and useful improvements in buildings and method of constructing the same and has as a primary object the elimination of unnecessary labor and waste in the constructing of a building.

Another object of this invention resides in the provision of an improved method of forming buildings from concrete in which ample air spaces are formed.

A further object of this invention resides in the provision of an improved method of constructing buildings wherein the material employed to brace the interior wall of the retaining form may be, after the walls have set, used to construct the partitions of the building without material change.

And a still further object of this invention resides in the provision of an improved manner of constructing buildings wherein the inner form retaining wall is made of inexpensive material adapted to remain in place after the walls have set.

With the above and other objects in view which will appear as the description proceeds, my invention resides in the novel construction, combination and arrangement of parts substantially as hereinafter described and more particularly defined by the appended claims, it being understood that such changes in the precise embodiment of the herein disclosed invention may be made as come within the scope of the claims.

In the accompanying drawing, I have illustrated two complete examples of the physical embodiment of my invention constructed according to the best modes I have so far devised for the practical application of the principles thereof, and in which:

Figure 1 is a fragmentary, sectional, perspective view taken transversely through one corner portion of a building under construction in which my invention is being employed;

Figure 2 is a fragmentary, sectional, perspective view taken through one wall of a building under construction and illustrating the application of a slightly modified form of my invention;

Figure 3 is a fragmentary sectional view illustrating the manner of securing the air channel form and the plaster base in position, and

Figure 4 is a view similar to Figure 2 of still another modification of my invention.

Referring now more particularly to the ac-

companying drawing in which like numerals designate like parts throughout the several views, the numeral 5 designates an outer movable retaining form of either metal or wood construction and adapted to be spaced from an inner retaining form, to be later described. The space 6 between the forms is filled with concrete 7 which, upon setting, constitutes the wall of the building. If desired rubble stones 8 may be inserted in the mold along the outer retaining form prior to pouring the concrete as is customary in the building art.

The inner retaining form consists of a plurality of vertically extending units each consisting of an elongated member 9 which may be of metal, heavy cardboard, fibre board or any other suitable material.

Each member 10 has its side marginal edge portions bent or folded inwardly upon its medial portion to form recesses 11 and the extreme marginal edges of the member are directly laterally and outwardly to form anchoring flanges 12 which extend into the mold or form space 6 and become embedded in the concrete. The members 9 have their longitudinal edges placed under compression to bow the same as illustrated and have their marginal edges engaged in the recesses of the member 10 to form the completed units. The members 9 being bowed as described form the units with vertical air channels or spaces 13 which are produced in the completed wall.

The members 10 are of the conventional metal lathe construction, or any other suitable construction to form a plaster base, although the use of a plaster board may be employed without departing from the spirit of the invention as illustrated in Figure 2.

The form units are secured into place with their marginal edges abutting by a brace frame 14 consisting of top and bottom plates or beams 15, but one being shown, connected by vertical studs 16, one stud 16 being positioned at the meeting edges of adjacent units as illustrated. The beams and studs are of a size suitable for interior partitions to permit their use in the building upon removal of the forms as later described.

The outer and inner retaining forms are maintained in proper spaced relation by spacer blocks 17 confined therebetween and engaging the inner wall at the meeting edge portions of the units, as clearly illustrated in Figure 1. The forms are held against

the spacer blocks by ties 18 preferably in the form of hooks which pass therethrough and have their inner ends 19 engaged over the adjacent studs 16 and their outer ends passed outwardly of the outer form through bracing studs 20 and there secured by wedges or other securing means 21. The corner studs 16 and 20 are tied together by wires or other means 22, as illustrated. If desired nailing blocks 17' may be provided.

With the form set up as described, the concrete 7 is poured after having suitable reinforcing members 23 placed therein if desired. When the concrete has set sufficiently, the wedges 21 are removed and the wires 22 cut and the bracing frame 14 utilized for the interior partitions, being cut to the various dimensions necessary. In this manner there is no waste of material, as the brace studing frames form braces as well as the interior partitions. The hooks 18 are removed and the plaster base 10 is plastered in the conventional manner. The members 9 remain in the walls as they are of any inexpensive material.

In that form of my invention illustrated in Figure 2, a very slightly modified construction is illustrated wherein the members 9 are secured to a sheet plaster base 10' by means of relatively long nails 24 which become embedded in the concrete and anchor or secure the sheet plaster base in place. As in that form of my invention illustrated in Figure 1, the up-right studs of the bracing frame are located adjacent the meeting marginal edges of the members 9 and are removed after the concrete has set and employed for interior partitions. If desired, wire ties 25 may be employed in lieu of the hooks 18.

From the foregoing description taken in connection with the accompanying drawing, it will be readily apparent to those skilled in the art to which an invention of this character appertains that I provide an improved method of building in which the cost of labor and material is reduced and a better construction is provided in that ample air space is obtained between the plaster wall.

It will also be apparent to those skilled in the art to which an invention of this character appertains that the members 9 being preferably of heavy cardboard, fibre or any other material having the ability to insulate against cold or heat afford means for absorbing any chill that may pass through the concrete wall 7 to, with the air spaces, provide additional protection. It will also be apparent that the nailing blocks 17', which are preferably of wood, afford means for facilitating the attaching the base board, picture moldings, panels, etc.

In Figure 4 a slightly modified construction is illustrated in which the studs 26 are a permanent part of the inner retaining

form and have the units 27 of heavy paper or suitable temperature insulating material secured therebetween, as at 28. The outer faces of the studs project beyond the units 27 so that when the finished wall 29 is laid the air spaces 30 are formed. The studs are anchored in the concrete and nails or other members 31 are preferably driven in the studs before pouring the concrete to provide additional anchoring means. The studs being incorporated in the finished wall provide means for nailing molding, base boards and the like in position.

I claim:

1. In a building construction, an outside retaining form, a fibrous inside retaining form of channel shape, an inside wall forming member bridging the channel of the inside form, and means whereby the inside wall forming member becomes anchored to the wall proper poured in the space between the outside and inside retaining forms. 80

2. In a building construction, an outside retaining form, an inside retaining form consisting of a plurality of units each having an inner channeled member connected with an outer plaster base, a bracing frame retaining the units in position, and means extending through the form and connecting the outside retaining form and the bracing form against spreading. 85

3. In a building construction, an outside retaining form, an inside retaining form consisting of a plurality of units each having an inner channeled member connected with a straight outer plaster base, and means retaining the units in position. 90

4. In a building construction, an outside retaining form, an inside retaining form consisting of a plurality of units each having an inner channeled member connected with an outer plaster base, and a bracing frame retaining the units in position, the marginal edges of the plaster base being projected into the space between the inner and outer retaining frames to provide anchors adapted to become embedded in the material poured between the forms. 105

5. In a building construction, an outside retaining form, an inside retaining form shaped to produce an air space in a wall resulting from pouring concrete between the forms, the inside form being of temperature insulating material and remaining in the wall upon completion, and means facilitating the laying of an interior finished wall over the concrete wall. 115

6. In a building construction, an outside retaining form, an inside retaining form including a plurality of members of temperature insulating material having their longitudinal edges of a different plane than their medial portions to produce air spaces in a wall resulting from pouring concrete between the forms, said inside retaining 125

form remaining in the wall after the concrete has set to afford insulation, and means facilitating the laying of an interior finished wall over the concrete wall and which is separated from the main body of the concrete wall by the air spaces.

7. In a building construction, an outside retaining form, an inside retaining form including a plurality of members of temperature insulating material having their longitudinal edges of a different plane than their medial portions to produce air spaces in a wall produced by pouring concrete between the forms, said inside retaining form remaining in the wall after the concrete has set to afford insulation, and brace members mounted adjacent the longitudinal edges of said insulating members to retain the same in position as the wall is poured.

20 8. In a wall construction, a form unit embodying longitudinal edges bent upon itself to provide longitudinal recesses, and a second member having its longitudinal edges engaged in the first member recesses and spaced therefrom to provide an air space between the members.

9. In a wall construction, a form unit embodying longitudinal edges bent upon itself to provide longitudinal recesses, a second 30 member having its longitudinal edges engaged in said recesses and spaced from the first-mentioned member to provide an air space between the members, and extensions carried by the bent edges of the first-mentioned member and adapted to be embedded

in a wall in which the members are incorporated to retain the same in position.

10. In a building construction, a wall mold adapted to have a plastic mass poured therein and comprising an outer form wall, an inner form wall including a plurality of vertical unit sections arranged with their longitudinal edges abutting, a bracing frame for the inner form wall and including vertical members adapted to engage the inner form wall at the meeting edges of the unit sections, spacing means in the mold to maintain the inner and outer walls in proper relation, and means extending through the mold and connecting the vertical members of the bracing frame with the outer form wall to prevent spreading between the walls.

11. In a building construction, a wall mold adapted to have a plastic mass poured therein and comprising an outer form wall, a plurality of vertical unit sections arranged with their longitudinal edges abutting to provide an outer form wall, each section including a channeled member and a plaster base retaining the same in channel shape, a 55 bracing frame for the inner form wall at the meeting edges of the unit sections, spacing means in the mold to maintain the inner and outer walls in proper relation, and means extending through the mold and connecting the vertical members of the bracing frame with the outer form wall to prevent spreading between the walls.

In testimony whereof I affix my signature.
PROSPER L. GOTTSCHALK.
